UNITED STATES PATENT OFFICE.

JEAN THEOBALD, OF NORTH ATTLEBOROUGH, MASSACHUSETTS, ASSIGNOR
TO THE FRANK M. WHITING & COMPANY, OF SAME PLACE.

DESIGN FOR A HANDLE FOR NAIL-FILES OR SIMILAR ARTICLES.

SPECIFICATION forming part of Design No. 29,433, dated October 4, 1898.

Application filed July 22, 1898. Serial No. 686,625. Term of patent 3½ years.

To all whom it may concern:

Be it known that I, JEAN THEOBALD, a citizen of the United States, residing at North Attleborough, in the county of Bristol, State 5 of Massachusetts, have invented and produced a new and original Design for the Handle of a Nail-File or Similar Article, of which the following is a specification, reference being had to the accompanying drawings, forming part thereof.

The drawings show my design, Figure 1 being a plan, and Fig. 2 a cross-section, applied to the handle of a nail-file.

The leading feature of my design is a 15 crowning shell ornament, entwined scroll ornamentation at the base, a scroll and husk combination intermediate the handle, and the resulting handle outline.

In the drawings, A represents the head, B 20 the stem, and C the base, of my handle.

The handle-head A is crowned by a shell ornament 1, flanked by inwardly-turned scrolls 2 2, whose lower heads embrace the husk 3 3, and surmount the minor scrolls 4 4. The 25 lower part of the head is formed by S-shaped

foliated scrolls 5 5, whose upper heads are the larger, with intermediate branching leaf foliates 6 6, overlying lesser scrolls 7 7. Between the lower heads of scrolls 5 5 is a husk 8, with lesser scrolls 9 9 on either side. 30

The stem of the handle is outlined by scrolls 10 10, converging at their lower extremities and inclosing minor scrolls, which bound a plain surface 11.

The base of the handle is formed by a double 35 foliated scroll ornamentation, whose branching members 13 14 intertwine. Inclosed is a plain surface 15.

Having thus described my invention, I 40 claim as new and desire to secure by Letters Patent

The design for the handle of a nail-file or similar article herein shown and described.

In witness whereof I have hereunto set my hand.

JEAN THEOBALD.
